UNITED STATES PATENT OFFICE.

ROBERT ZINSMAYER, OF SANDUSKY, OHIO, ASSIGNOR OF THREE-TENTHS TO ALBERT KRAPP AND THREE-TENTHS TO CHARLES L. BLATZ, BOTH OF SANDUSKY, OHIO.

SUPPORT FOR TELEPHONE-RECEIVERS.

949,814.

Specification of Letters Patent. Patented Feb. 22, 1910.

Application filed May 7, 1909. Serial No. 494,551.

To all whom it may concern:

Be it known that I, ROBERT ZINSMAYER, a citizen of the United States, residing at Sandusky, in the county of Erie and State 5 of Ohio, have invented new and useful Improvements in Supports for Telephone-Rec-
eivers, of which the following is a speci-
fication.

The purpose of this invention is to sup-
10 ply novel means for holding the receiver
of a telephone in convenient operative posi-
tion when in use so as to leave both hands
free for the taking of notes, handling papers
or for any desired purpose thereby avoid-
15 ing the inconvenience, fatigue and annoy-
ance incident to using one hand for hold-
ing the receiver to the ear.

The invention has for its object to pro-
20 vide a support of the nature aforesaid which
may be readily applied to telephones gener-
ally in use, it being understood that the
appliance is provided in a form to meet the
style and nature of instrument in use in any
particular locality.

25 A further purpose of the invention is the
provision of a support for the receiver of
a telephone which admits of adjustment
to adapt the receiver to the convenience of
the person using the instrument, also to
30 provide novel and peculiar connections
whereby the usual receiver hook may be
operated automatically to throw the instru-
ment into and out of connection.

35 The invention consists of the novel fea-
tures, details of construction and combina-
tions of parts which hereinafter will be
more particularly set forth, illustrated in
the accompanying drawings and pointed out
in the appended claims.

40 Referring to the drawings forming a part
of the specification: Figure 1 is a view in
elevation of a telephone instrument of the
desk type provided with a receiver support
and operating means for the receiver em-
bodying the invention, the full lines show-
45 ing the receiver supported in operative
position and the dotted lines illustrating
the position of the receiver when lowered
and the instrument cut out. Fig. 2 is a
50 side view of the receiver showing the clip
or attaching means for connecting the same
to the supporting arm. Fig. 3 is a perspec-
tive view of the presser bar lever.

Corresponding and like parts are referred

to in the following description and indi- 55
cated in all the views of the drawings by
the same reference characters.

The appliance comprises a support 1 for
receiving the operating parts, said sup-
port being secured to the instrument in any 60
manner according to the type or make of
instrument. A clip 2 is provided at the
lower end of the support 1 and serves as
securing means for attaching said support
to the stand 3 of the telephone instru- 65
ment. A series of ratchet teeth 4 are pro-
vided along the upper portion of the
support 1 and are adapted to coöperate
with the receiver supporting arm 5 to hold
the same in an adjusted position. An arm 70
6 is secured at 7 to the support 1 and is
provided at its free end with a cross head
8 to provide an extended bearing for the
arm 5 when the latter is elevated into opera-
tive position. The inner end of the receiver 75
supporting arm 5 terminates in a point
which is adapted to engage with the teeth
4 so as to hold the arm in the required ele-
vated position. A longitudinal slot 9 is
formed in the inner end portion of the arm 80
5 and receives an expansion spring 10 which
normally presses the pointed end of the arm
5 into engagement with the coöperating
ratchet teeth 4 so as to prevent casual dis-
placement of the inner end of the arm there- 85
from. A pin or headed stud 11 secured to
the pivoted arm 6 is arranged to operate
in the longitudinal slot 9 and serves to con-
nect the receiver supporting arm 5 to the
arm 6. The longitudinal slot 9 admits of 90
the arm 5 having a limited longitudinal
movement whereby its inner end may be
engaged with or disengaged from the teeth
4. The spring 10 obtains a bearing at one
end against the fastening 11 and at its op- 95
posite end upon the inner closed end of the
slot 9, hence, the spring normally serves
to press the arm 5 inward or toward the
support 1.

The receiver 12 may be connected to the 100
outer end of the arm 5 in any manner. As
shown, a clip or support 13 embraces the re-
ceiver 12 between its ends and is attached
to the bent end 14 of the supporting arm 5.
The clip or support 13 may be of any con- 105
struction to firmly and securely hold the re-
ceiver but yet admit of the receiver being
readily detached therefrom or placed in po-

sition. The clip 13 is also of such construction as to prevent its marring the receiver in any manner.

The hook for supporting the receiver is indicated at 15 and is of ordinary construction and operation. When the hook is depressed the talking circuit is interrupted and the bell circuit established and vice versa. Inasmuch, as the receiver 12 is not suspended from the hook 15 in accordance with the present invention, it is necessary to provide equivalent means for operating the hook 15 whereby the talking circuit may be interrupted when the receiver is lowered and established when the receiver is elevated into operative position. For this purpose a presser bar 16 is provided and is arranged so that its lower end is in contact with the receiver hook 15. A lever 17 is pivoted to the support 1 at 18 and is of the bell crank type, its short arm 19 being pivoted to the upper end of the presser bar 16 and its long arm terminating in a lateral extension 20 which projects into the path of the arm 5 to be engaged thereby and when the receiver is lowered as indicated by the dotted lines in Fig. 1 thereby depressing the bar 16 and the receiver hook 15.

The invention may be readily adapted to different styles and makes of instruments, it being understood that in certain localities certain types of instruments predominate and the attachment may be constructed so as to be readily adapted to these instruments. The support 1 is provided with attaching means whereby it may be firmly and readily secured to the instrument, the coöperating parts attached to the support 1 being relatively disposed for conjoint use with the parts of the instrument to which the appliance is fitted.

When the arm 5 is moved from the dotted line position indicated in Fig. 1 to the operative position shown by full lines, the inner pointed end of said arm automatically engages with the ratchet teeth 4. As the arm 5 is elevated at its outer end, and the lever 17 is released and the receiver hook 15 being relieved of the weight of the receiver rises in the well known manner thereby throwing the talking circuit into operation. When through using the instrument, the arm 5 is drawn outward a distance to disengage its inner end from the ratchet

teeth so that the arm may be swung into a pendent position and coming in contact with the lateral extension 20 of the lever 17 operates the latter and depresses the bar 16 whereby the receiver hook 15 is lowered.

From the foregoing description, taken in connection with the accompanying drawing, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the claims appended hereto.

Having thus described the invention, what is claimed is—

1. In means for supporting the receiver of a telephone, the combination of a support provided with a series of ratchet teeth, an arm projected from said support, an arm carrying the receiver and provided near its inner end with a longitudinal slot, a fastening extended into the slot of the receiver arm and carried by the arm extended from said support, and a spring located in said slot and normally pressing the receiver arm inward to hold its inner end in engagement with any one of the series of ratchet teeth. 75

2. In means for supporting the receiver of a telephone, the combination of a support provided with a series of ratchet teeth, an arm projected from the support, a receiver arm both pivotally and slidably connected to the arm extended from said support, and adapted to engage with any one of the series of ratchet teeth of said support, a spring 80 coöperating with the receiver arm for normally pressing the same inward, a lever extended into the path of the receiver arm, and a presser bar adapted to be actuated by said lever for depressing the receiver 85 hook. 90

In testimony whereof I affix my signature in presence of two witnesses.

ROBERT ZINSMAYER.
